COMPACT

Nathan Kasdan, Plainfield, Conn., assignor to Majestic Metal Specialties, Inc., Moosup, Conn.,
a corporation of Connecticut

Application January 16, 1952, Serial No. 18,087

Term of patent 7 years

(Cl. D86—10)

To all whom it may concern:

Be it known that I, Nathan Kasdan, a citizen of the United States, and a resident of Plainfield, in the county of Windham and State of Connecticut, have invented a new, original, and ornamental Design for Compact, of which the following is a specification, reference being had to the accompanying drawing, forming a part thereof, wherein:

Fig. 1 is a plan view of a compact showing my new design;

Fig. 2 is a bottom view thereof;

Fig. 3 is a side elevation thereof; and

Fig. 4 is a view similar to Fig. 3, but with the cover of the compact in open position.

I claim:

The ornamental design for a compact, substantially as shown.

NATHAN KASDAN.
